UNITED STATES PATENT OFFICE

KENT A. HAWLEY, OF BALTIMORE, MARYLAND, ASSIGNOR TO LOCKE INSULATOR CORPORATION, OF BALTIMORE, MARYLAND, A CORPORATION OF MARYLAND

CUSHION FOR INSULATOR PINS AND METHOD OF APPLYING

Application filed February 3, 1927. Serial No. 165,650.

The invention relates to insulators, particularly that type embodying a dielectric body such as porcelain, having a recess within which is cemented a metallic pin or its equivalent.

In insulators of many types, for instance pedestal, bus bar, suspension and others, embodying a porcelain body having a recess within which is cemented a suspension pin,

supporting post or the like, it has been generally found necessary to provide some sort of cushion or yieldable means interposed between the metal and the cement so as to prevent the bringing of crushing strains upon the cement as the result of thermal changes, and to insure conforming engagement against the cement by filling inequalities which may exist in the surfaces. Ordinarily it has been found that a coating of asphaltum or the like, of course applied in melted condition, is reasonably efficient. However, in some instances it has been demonstrated that the thickness of such coating is insufficient at the end of the pin.

It is with the above facts in view that I have designed the present invention which has for its general object the provision of a cushion adapted to be secured upon or attached to the end of the pin, or its equivalent, the invention further contemplating a novel method of and means for holding the cushion in place so that it cannot become displaced or dislocated from its proper position during assembly of the insulator.

More specifically, the object of the invention is to provide cushioning means in the nature of a disk or pad of yieldable material disposed upon the end of the pin, or its equivalent, and held in place by an adhesive.

Another object of the invention is to provide a cushion or pad of this character which, when used in connection with a hollow open ended pin, post or the like, will act as a dam to prevent the cement within the pin receiving recess from entering the hollow pin itself.

An additional object of the invention is to provide cushioning means and a method of applying the same which will be simple and inexpensive in so far as labor and materials are both concerned, efficient and positive in

use, durable in service, and a general improvement in the art.

To the attainment of the foregoing and other objects and advantages, the invention consists in the detailed structure, the arrangement and combination and the method steps to be hereinafter more fully described and claimed, and illustrated in the accompanying drawing in which:

Figure 1 is a sectional view, partly in elevation, of an insulator of the cap and pin type showing the invention applied,

Figure 2 is a similar view of an insulator of the pedestal type embodying a hollow open ended pin and showing the invention applied.

Referring more particularly to the drawing, and especially Figure 1, the numeral 1 designates the porcelain body of a suspension insulator of the type having a stem 2 carrying a cap 3, the body also having a recess 4 within which is secured, by cement 5, a metallic suspension pin 6. The type of cap and pin may of course be varied as the details thereof form no part of the present invention which contemplates simply the provision of a cushion to be interposed between the end of the pin and the bottom of the recess within which it is received and secured.

In carrying out the invention I provide a pad 7 which may conveniently be a disk of paper, rubberoid or other more or less similar yieldable material but which is preferably of such a nature as to be impervious to moisture and not subject to disintegration under the influence of the chemicals which are naturally present in the cement used for holding the pin in place. It is preferable that the pad 7 cover the end of the pin, or at least substantially so, and it is here represented as having practically the same diameter as the pin head. The thickness of the pad is a matter which may be varied and it would naturally depend to a certain extent upon the size of the insulator, its exact type and the character of the installation of which it is a part.

To avoid displacement of the disk with respect to the pin during assembly of the parts of the insulator, it becomes necessary to provide some means for holding the disk on the

pin and preventing it from slipping down onto the side thereof. Experimentation has demonstrated that the most suitable material to use as an adhesive is hot asphalt as it is capable of withstanding the chemicals in the cement. The method of applying need consist only in coating the end or as much of the pin as desired with the hot asphalt, either by swabbing it on or by dipping and then in placing the pad or disk in position. Clearly, as soon as the asphalt or its equivalent sets, the pad will be held firmly so that it cannot become displaced during handling of the pin preparatory to or during assembly of the insulator.

In Figure 2 I have illustrated an insulator of the pin or pedestal type here shown as including a plurality of nested porcelain shells 8, 9 and 10, the latter of which is formed with a recess 11 for the reception of the pin 12 which may rise from a base or be attached to some support. In some instances, pins of this type are hollow and if so are usually open at the upper end. The invention is carried out in connection with this type of pin in exactly the same manner as above described, the pad 13 being placed in position and secured by the hot asphalt indicated at 14. The employment of such a pad or cushion in connection with an insulator of this type embodying a hollow pin is particularly advantageous in that it not only provides the yielding substance between the metal of the pin and the bottom of the recess, but also constitutes a dam, seal or closure for the open end of the pin so that when the insulator is subsequently assembled and cement applied for securing the pin in the recess, the cement will be excluded from the interior of the pin.

From the foregoing description and a study of the drawing it will be apparent that I have thus provided a very simple cushioning means for and method of applying the same to insulator pins of all types for accomplishing the desired purpose. The cost of the materials necessary is extremely low and hardly any time or skill will be required to apply and secure the pads upon the pins. It is really believed that the construction, operation and advantages will be readily apparent to one skilled in the art without further explanation.

While I have shown and described the preferred embodiment of the invention and have mentioned certain relative sizes and specific materials, it should be understood that there is no particular restriction in these respects and that the right is reserved to make all such changes as will not depart from the spirit of the invention or the scope of the claims hereunto appended.

Having thus described the invention, I claim:

65 1. In an insulator, a porcelain body having

a recess therein, a metal pin cemented within the recess, and cushioning means interposed between the end of the pin and the bottom of the recess, said cushioning means comprising a yieldable disk secured upon the end of the pin, the securing means for the disk consisting of bituminous material applied in melted condition.

2. In an insulator including a porcelain body having a recess therein, and a metal pin cemented within the recess, the pin being hollow and having its end within the recess open, and a disk of yieldable material secured upon the end of the pin by an adhesive and constituting combined cushioning means and dam, the latter purpose being to exclude cement from the interior of the pin.

3. The method of securing a yieldable pad upon the end of an insulator pin prior to its cementing within a recessed porcelain body, comprising coating the end of the pin with bituminous material in a hot melted condition, and placing the pad upon the end of the pin whereby the bituminous material will act as an adhesive.

4. In an insulator, a porcelain body having a recess therein, a metal pin cemented within the recess, and a yieldable pad secured upon the end of the pin by bituminous adhesive material.

In testimony whereof I affix my signature.

KENT A. HAWLEY.
